CLOTHES HANGER

BACKGROUND OF THE INVENTION

The present invention relates to clothes hangers, and more particularly to improvements in nonreversible clothes hangers which consist of synthetic plastic material.

The arms of certain conventional clothes hangers have the shape of a cylinder cut in half along its axis. The ends of the arms are bent from the general plane of the clothes hanger so that the tips of such arms leave unsightly marks on garments which are suspended thereon, especially if the garments are tightly packed on a clothesrack. Such marks are particularly undesirable when the clothes hangers are used in a store. Furthermore, the just-mentioned conventional clothes hangers occupy too much room in a closet or on a display rack.

SUMMARY OF THE INVENTION

It is, therefore, an object of the present invention to overcome the disadvantages of conventional clothes hangers and to provide a clothes hanger which produces no pressure marks on suspended clothes, no matter how tightly they are packed next to each other.

Another object is to provide a compact clothes hanger.

A further object of the invention is to provide a clothes hanger which can be produced at low cost.

The invention resides in the provision of a clothes hanger which comprises two mirror symmetrical hollow arms each of which includes two walls having edges at least one of which curves to a point located inwardly of the tip of the respective arm and meets the other edge in the region of such point. The walls of each arm preferably meet and form a bottom wall which extends from the aforementioned point to the tip of the respective arm.

The novel features which are considered as characteristic of the invention are set forth in particular in the appended claims. The improved clothes hanger itself, however, both as to its construction and the mode of utilizing the same, together with additional features and advantages thereof, will be best understood upon perusal of the following detailed description of certain specific embodiments with reference to the accompanying drawing.

BRIEF DESCRIPTION OF THE DRAWING

FIG. 1 is a fragmentary elevational view of a clothes hanger which embodies one form of the invention;

FIG. 2 is a view as seen in the direction of arrows from the line II-II of FIG. 1;

FIG. 3 is a fragmentary elevational view of a second clothes hanger;

FIG. 4 is a fragmentary elevational view of a third clothes hanger;

FIG. 5 is a fragmentary sectional view as seen in the direction of arrows from the line V-V of FIG. 4;

FIG. 6 is a sectional view as seen in the direction of arrows from the line VI-VI of FIG. 4;

FIG. 7 is a sectional view of a fourth clothes hanger taken on a section line similar to line VI-VI but in the hanger of FIG. 7; and

FIG. 8 is a sectional view of a fifth clothes hanger taken on a section line similar to line VI-VI but on the hanger of FIG. 8.

DESCRIPTION OF THE PREFERRED EMBODIMENTS

FIG. 1 illustrates a clothes hanger 1 which is suspended on a rotatably attached hook 2 and has two arms 3 (only one shown) extending in opposite directions from the center of the clothes hanger. The arms 3 are hollow and each thereof has an open side or slit which extends from its inner end toward and close to its outer end or tip 10. Each arm 3 further comprises two sidewalls 8 and 9 which flank a pocket 7 and meet at the tip 10 of the respective arm 3 to form a substantially horizontal web or bottom wall 11 which extends from the tip 10 toward a point 6 located inwardly of such tip, i.e., at the outer

end of the respective open side of the arm 3. The walls 8, 9 have elongated edges 4, 5 the outer portions of which curve toward the point 6 and meet at such point, namely, at the inner end of the respective bottom wall 11. FIG. 1 shows that the arms 3 taper (i.e., that their width decreases) in a direction from the tip 10 toward the point 6. The thickness of the walls 8, 9 is indicated by a dashed line 13. A hook 14, integral with the web 11 in the region of the point 6, extends toward the tip 10. FIG. 2 shows that portions of the walls 8, 9 are parallel to each other and that their outer ends are rounded to form the bottom wall 11.

The clothes hanger of FIG. 3 has two hooks 16 and 17 attached in tandem to the bottom wall 11 at the outer end of the pocket 7 so that it can support a plurality of articles, such as skirts.

FIG. 4 shows that the outermost part of the arm merges into a horizontal crossbar 20. The edges 4 and 5 merge into the upper portion 19 of the crossbar 20, and the web merges into the lower portion 22 of the crossbar. In this embodiment the lower part of the pocket 7 is flanked by the bottom wall and by an extension 21 thereof, leading to the upper portion of the crossbar 20.

FIG. 5 shows the shape of the pocket 7 in the arm 3, with substantially parallel sidewalls 8 and 9 which curve increasingly toward each other at the end where the crossbar 20 is attached. FIG. 6, 7 and 8 illustrate various locations where the crossbar 20 may be placed at the respective ends of the arms. In FIG. 6 it is shown at the center, in FIG. 7 it is shown displaced in one direction relative to the center, and in FIG. 8 it is shown displaced in the opposite direction relative to the center. The pocket 7 may be enclosed from all sides. This further increases the stability of the arms and reduces the likelihood of damage to suspended garments.

All embodiments of the improved clothes hanger share the advantage of reducing the likelihood of damage. The invention provides for the placing of the relatively sharp hanger edges to an area where there is either no significant pressure from adjacent hangers, or where such pressure, if any, does not affect the suspended clothing. The pockets substantially increase the structural rigidity and stability and further contribute to an advantageous distribution of contact and pressure forces. The hooks are attached so that they are not likely to connect with and catch on to clothes on the respective hangers; because of the stability of the hangers, and their resistance to warping, the hooks can support without difficulty, the weight of the clothes that are to be suspended thereon. The crossbar which, according to a preferred embodiment, is joined to the lower wall of the pocket also contributes to the stability of the hanger and serves as a support for trousers or the like, and further makes it possible to give the hanger an even more favorable contour.

It will be understood that each of the elements described above, or two or more together, may also find a useful application in other types of clothes hangers differing from the types described above.

While the invention has been illustrated and described as embodied in clothes hangers, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What we claim as new and desired to be protected by Letters Patent is set forth in the appended claims.

1. A clothes hanger, comprising a pair of arms diverging downwardly and outwardly away from one another and each having a free tip, each of said arms being constituted by a con-

tinuous strip portion of sheet material having at least in the region of said free tip two transversely spaced longitudinally extending sidewalls and a bottom wall between said sidewalls extending from said free tip inwardly to a point spaced from said free tip so as to form together with said sidewalls a pocket extending from said free tip to said spaced point.

2. A clothes hanger as defined in claim 1, wherein the respective pockets are enclosed at least from three sides.

3. A clothes hanger as defined in claim 1, wherein portions of said sidewalls on each of said arms are substantially parallel to each other.

4. A clothes hanger as defined in claim 1, further comprising at least one hook provided on each of said arms, each of said hooks extending from said point toward but short of the free tip of the respective arm.

5. A clothes hanger as defined in claim 1, further comprising a pair of hooks each rigid with one of said arms adjacent to the respective point.

6. A clothes hanger as defined in claim 1, further comprising a crossbar attached to said arms and extending between said points.

7. A clothes hanger as defined in claim 6, wherein said crossbar has an upper portion and said sidewalls merge into said upper portion of said crossbar.

8. A clothes hanger as defined in claim 6, wherein said crossbar has a lower portion, and wherein the respective bottom walls merge into said lower portion at the respective ends of said crossbar.
